[57] CLAIM

The ornamental design for a “brooder hanger,” as shown and described.

DESCRIPTION

FIG. 1 is a perspective view of a brooder hanger;
FIG. 2 is an enlarged top plan view thereof;

FIG. 3 is a side view thereof;

FIG. 4 is an opposite side view thereof;

FIG. 5 is a front view thereof;

FIG. 6 is a rear view thereof; and,

FIG. 7 is a bottom view thereof.

The broken line showing of an element is for illustrative purposes only and forms no part of the claimed design.
